UNITED STATES PATENT OFFICE

LOUIS LUMIERE, OF LYON, FRANCE

TALKING MACHINE

Application filed April 30, 1925, Serial No. 27,024, and in Great Britain May 26, 1924.

This invention relates to improvements in talking machines and in particular to improvements in the mounting of the needle holder upon the ring or casing in which the diaphragm is mounted.

The object of the invention is to obtain a more effective transmission of the vibrations of the reproducing needle to the diaphragm.

Hitherto, the common practice in talking machines has been to mount the needle holder upon the diaphragm holding ring, or upon the sound box, so that it oscillates about an axis lying in or parallel to the plane of the diaphragm. According to the present invention the needle holder is mounted to oscillate about an axis lying at right angles to the plane of the diaphragm. The present invention is particularly applicable in connection with diaphragms of large diameter. These diaphragms, which may be 12 or more inches across, are usually mounted in a holding ring which in turn is carried on one side by a spider. Although these rings are made as rigid as possible, they nevertheless, of course, present greater rigidity in the direction of the plane of the diaphragm than they do in a direction at right angles to that plane. The part upon which the oscillating needle holder is mounted should be as rigid and as resistant as possible, in order that the vibrations of the needle point may be transmitted without loss to the diaphragm and with a needle holder mounted in accordance with the present invention the diaphragm holding ring opposes its greatest rigidity to the vibrations of the needle.

One method of carrying out the invention is illustrated in the accompanying drawings in which

Fig. 1 is a part elevation of a diaphragm of large diameter in which the needle holder is mounted in accordance with the present invention.

Fig. 2 is a sectional side elevation taken on the line 2—2 of Fig. 1.

The diaphragm *x* is mounted in a ring *a* folded over the edge of the diaphragm and clamped thereon. The diaphragm is, in the construction illustrated, mounted to play in a vertical position. On the edge of the ring

a, at the point nearest to the record when playing, is mounted a metal block *b*, secured by means of screws *c* or the like passed through the ring *a*. The block *b* may have the cross sectional form shown in Fig. 2 of 55 the drawings, a recess *d* being provided for the reception of the edge of the ring *a*. The needle holder *e* is mounted upon the block *b*, being carried, for example, in well known manner upon a stiff leaf spring *f*, having a 60 very high vibration frequency, one end of said spring *f* being clamped between metal plates *g*, *h*, which are in turn screwed or bolted to the block *b*, while the other end is clamped between a plate *k* and the needle 65 holder *e*. Between a pair of spring arms *m* extending laterally on one side of the needle holder *e* is secured one end of a transmission bar *n* running substantially radially of the diaphragm towards its centre, where it is 70 connected with the centre of the diaphragm by means of an oscillating bell crank lever *o* and a rod *p*, said lever *o* being mounted for example upon the centre boss *q* of the 75 spider *s* by an arrangement substantially similar to that by means of which the needle holder *e* is secured to the block *b*. In the form shown the boss *q* is provided with a small opening in its center, but said opening 80 may be omitted without affecting the operation of the device.

It will be readily seen that in the arrangement above described, the axis of oscillation of the needle holder *e* lies at right angles to the plane of the diaphragm.

With the arrangement above described, the stresses communicated to the diaphragm holding ring by the vibration of the needle holder during reproduction are in a direction in or parallel to the plane of the diaphragm and of the diaphragm holding ring, and the maximum resistance is offered to any movement of the plates *g*, *h* holding the spring. It will also be understood that where 90 the diaphragm is arranged to play in a vertical position these stresses are communicated to the diaphragm holding ring in a direction which runs substantially through the centre 95 of gravity of the diaphragm holding ring.

I claim:

1. Apparatus of the class described comprising diaphragm means having a needle holder resiliently mounted thereon to oscillate about an axis lying substantially at right angles to the plane of the diaphragm.
2. Apparatus as claimed in claim 1, said needle holder being carried by a leaf spring lying in a plane at right angles to the plane of the diaphragm, said spring being secured at one end to the needle holder and at the other end being operatively connected to the diaphragm means.
3. In apparatus of the class described, the combination of a diaphragm, a diaphragm holding ring, a needle holder mounted on said ring to oscillate about an axis substantially at right angles to the diaphragm, and means including a longitudinally movable transmitting arm for transmitting the oscillations of the needle holder to the diaphragm.
4. In a device of the class described, a diaphragm, a diaphragm holding ring, a needle holder, resilient means for mounting said holder on said ring to oscillate about an axis substantially at right angles to the plane of the diaphragm, and means including a transmitting arm operatively connecting the diaphragm and needle holder for transmitting oscillations of the latter to the diaphragm.
5. In a device of the class described, a diaphragm, a diaphragm holding ring, a needle holder, resilient means for mounting said needle holder on said ring, said means extending substantially at right angles to the plane of the diaphragm and supporting said needle holder to oscillate about an axis substantially at right angles to said diaphragm, a transmitting arm operatively connected to said needle holder, and means for connecting said transmitting arm with said diaphragm.
6. In a device of the class described, in combination, a diaphragm, a needle holder resiliently mounted to oscillate about an axis substantially at right angles to said diaphragm, operative connections between said needle holder and diaphragm, and common means for mounting said needle holder and diaphragm, said means being so constructed and arranged that the stresses received by said mounting means from said needle holder being exerted in a direction substantially parallel to the plane of the diaphragm.
7. In apparatus of the class described, the combination of a diaphragm, a diaphragm holding ring, a needle holder mounted on said ring to oscillate about an axis substantially at right angles to the plane of the diaphragm, and means including connections pivoted about a substantially horizontal axis substantially at right angles to said first axis for transmitting the oscillations of said needle holder to the diaphragm.
8. In a device of the class described, a diaphragm, a diaphragm support, a needle hold-

er mounted on said support to oscillate about an axis substantially at right angles to the plane of the diaphragm, a transmitting arm operatively connected to said needle holder, and means including a bell crank lever mounted on said support for connecting said transmitting arm with said diaphragm.

9. In a device of the class described, a diaphragm, a diaphragm support, a needle holder, resilient means for mounting said needle holder on said support to oscillate about an axis substantially at right angles to the plane of the diaphragm, a transmitting arm operatively connected to said needle holder, and a bell crank lever resiliently mounted on said support, one arm of said lever being connected to said transmitting arm and the other arm to said diaphragm.

10. In a device of the class described, a diaphragm, a diaphragm support, a needle holder, resilient means for mounting said needle holder on said support to oscillate about an axis substantially at right angles to the plane of the diaphragm, a transmitting arm operatively connected to said needle holder, a bell crank lever, and resilient means for mounting said lever on said support to oscillate about an axis substantially parallel to the plane of the diaphragm, one arm of said lever being connected to said transmitting arm and the other arm to said diaphragm.

In testimony whereof I have signed my name to this specification.

LOUIS LUMIERE.
